UNITED STATES PATENT OFFICE

GEORGE B. GLIDDEN, OF Dighton, MASSACHUSETTS, ASSIGNOR TO GEORGE FROST COMPANY, OF BOSTON, MASSACHUSETTS

GARTER

Application filed December 6, 1930. Serial No. 500,620.

This invention relates to new and useful improvements in garters of the leg-encircling type, and has for its principal object to provide a single piece pad which is centrally 5 folded to form opposed leaves between which one end of the limb encircling band, the hose supporting means, and a part of one of the band fastening means is disposed; whereby an extremely simple and practical garter is 10 constructed.

In the accompanying drawings:

Figure 1 is a plan view of a garter constructed in accordance with my invention;

Figure 2 is a fragmentary plan view of the 15 reverse side of the pad end of the garter;

Figure 3 is a cross-sectional view taken on the line 3—3 of Figure 1;

Figure 4 is a plan view of the blank from 20 which the pad is formed;

Figure 5 is a perspective view of the eye member which forms a part of the band connecting means, and

Figure 6 is a modified form showing another means of attaching the eye member to 25 the pad.

Referring to the drawings, my invention includes a pad A, a leg-encircling band B, connecting members C and D for the band, and a hose supporting means E.

The pad A is preferably formed from a 30 single blank of leather as shown in Figure 4. This blank is folded centrally between its ends, as indicated by the dotted line 5 in Figure 4, to form resultant opposed leaves 6—6.

The ends 7—7 of the leaves 6—6 opposite the 35 fold line 5 are disposed in register and in a plane at an angle to said fold line.

The leg-encircling band B has one end inserted between the leaves 6—6 of the pad.

The connecting element C is attached to the 40 free end of the band and includes a hook 8. The connecting member D includes an open frame 9 which includes parallel bars 10—10 and an intermediate bar 11 which is formed

45 into an eye 12. The side bars 10—10 are positioned between the leaves 6—6 of the pad and the intermediate bar 11, together with the eye 12, is positioned exteriorly of the pad as shown in Figure 1.

50 The hose supporting devices E include a

button support 13, a cooperating clasp 14 and a hanger 15, the latter being folded into a loop having its free ends disposed between the leaves 6—6 of the pad.

A single line of stitches 16 is formed in 55 substantially triangular shape and serves to connect the anchoring end of the band B, the hanger E and both leaves 6—6 together. One leg 17 of the triangular line of stitches extends parallel to the inner bar 10 of the connecting device D and functions to hold 60 said device against the folded edge 5 of the pad.

From the foregoing it will be observed 65 that I have provided a garter of the leg-encircling type which is composed of but very few members, is, therefore, very simple in construction and is cheap to manufacture. It will also be observed that by means of the pad A the connecting device D, which is of 70 metal, is easily assembled, is firmly retained in place and is maintained against direct contact with the leg of the wearer.

In the modified form shown in Figure 6 I have attached a connecting member Z directly 75 to the outer face of one of the leaves 6 of the pad A by means of stitches 18, said member Z being provided with an eye 19 for cooperation with the hook 8.

I claim as my invention:

In a garter, the combination with a pad 80 formed of a single piece of material centrally folded to form resultant opposed leaves; hose supporting means including a leg-encircling band and a hanger disposed between 85 the leaves of the pad; the leaves of the pad, band and hanger being secured together by stitches; and band fastening means comprising a hook member and an eye member, one 90 of said members being attached to the free end of the band, the other member including a rectangular frame disposed within the leaves of the pad between the fold line and the anchored end of the band, and an intermediate cross bar disposed exteriorly of the 95 pad and forming the connecting element of the member.

In testimony whereof, I have hereunto 100 subscribed my name.

GEORGE B. GLIDDEN.
